UNITED STATES PATENT OFFICE.

HENRY WILLIAM ROELING, ANDREW GEORGE KERN, JOHN GEORGE BAUER, AND
JOSEPH CATALANO, JR., OF NEW ORLEANS, LOUISIANA.

RAILWAY SIGNAL DEVICE.

Application filed June 5, 1922. Serial No. 565,958.

To all whom it may concern:

Be it known that we, HENRY WILLIAM ROELING, ANDREW G. KERN, JOHN G. BAUER, and JOSEPH CATALANO, Jr., citizens of the 5 United States, residing at New Orleans, in the parish of Orleans and State of Louisiana, have invented certain new and useful Improvements in Railway Signal Devices; and we do hereby declare the following to 10 be a full, clear, and exact description of the invention, such as will enable others skilled in the art to which it appertains to make and use the same.

The present invention relates to railway 15 signal devices and has for an object to provide an improved device in the engine cab for notifying the engineer plainly of the position of the semaphore guarding the block which he is about to enter.

20 Other objects of the invention are to simplify the construction of signals, to provide a device for securing a high degree of safety in the operation of railroad trains and the like, to enable the device to be installed in 25 connection with semaphore signals and the locomotive structure without requiring any alteration in standard constructions and to provide a device which is simple in its construction, reliable in its operation and economical to make.

With the foregoing and other objects in view, the invention will be more fully described hereinafter, and will be more particularly pointed out in the claims appended 35 hereto.

In the drawings, wherein like symbols refer to like or corresponding parts throughout the several views,

Fig. 1. is a diagrammatic view showing 40 the railway track in section with a semaphore signal and a locomotive equipped with a device according to the present invention.

Fig. 2. is a sectional view on an enlarged scale of the circuit controller.

45 Fig. 3. is a transverse sectional view taken on the line 3—3 in Fig. 2.

Fig. 4. is a similar view taken on the line 4—4 also in Fig. 2.

50 Fig. 5 is a central section taken through a relay employed.

Fig. 6. is a circuit diagram showing the relation of the various units in an open circuit arrangement, and

Fig. 7. is a similar view of a closed circuit arrangement.

55

Referring more particularly to the drawings 1 designates generally a locomotive upon the track 2 and 3 indicates a standard supporting the semaphore signal 4.

According to the invention a pair of bevel 60 gears 5 are adapted to mesh and be rotated by changes in the position of the semaphore arm, these gears being situated at the base, of the standard 3 and in connection to rotate a shaft 6 that extends transversely beneath 65 the rails 2. Bearings 7 support the shaft which carries a pair of trip arms 8 and 9 projecting at substantially 90 degrees apart.

Upon the locomotive are carried controllers 10 and 11 having fingers 12 and 13 70 adapted to project in the path of the arms 8 and 9 to be actuated thereby. The controllers are in circuit with relays 14 and 15 in the engine cab or at other suitable points therein and these relays are in turn in circuit with signal lamps 16 and 17 also carried by the locomotive. It is to be understood that the relays and lamps are shown only diagrammatically in Fig. 1 and in practice they would probably be located in 80 the engineer's side of the cab directly in front of the throttle lever where the lamps would come at all times under the observation of the engineer.

Referring more particularly to Figs. 2, 3, 85 and 4, one of the controllers 11 is shown in detail embodying a shaft 18 which projects up axially through the controller casing 11 and is journaled in bearings 19 and 20 carried by the closed end of the casing and by 90 the removable cover 21 which is secured to the open end of the casing as by the screws 22. The shaft 18 extends downwardly below the casing and the cover 21 and carries upon its lower end the arm 13.

95 Within the casing is a drum 23 secured to the shaft 18 as by the use of a pin 24. This drum or conductor body 23 is made of brass or other appropriate conducting material and is provided with diametrically disposed pockets 24 and 25 for receiving the insulating segments 26 and 27 which lie flush with the periphery of this conducting drum-like structure 23. A pair of brushes 28 and 29 are arranged to bear against the 105 drum at opposite sides and are curved on

their inner faces to conform to the curvature of the drum. These brushes are provided with pins 30 slidably received in hollow bosses 31 projecting inwardly from insulating plates 32 carried by the casing 11. Binding screws or bolts 33 are threaded through the casing and through the plates 32 and are connected to the brushes by coil springs 34 which normally press the brushes 10 yielding against the surface of the drum.

Binding nuts 35 act to lock the bolts 33 in adjusted position thus permitting of a regulation of the tension of the coil springs.

The shaft 18 below the cover 21 carries an arm 36 normally held in an intermediate position by two oppositely acting springs 38 attached to the arm 36 and to the studs 39 on the cover. The arm 36 has bifurcated ends 40 adapted to receive a tightening bolt 41 by which the arm is effectively gripped to the shaft 18.

Referring now to Fig. 5, the improved relay is shown to consist of a magnet or solenoid 42 situated above and resting upon the casing 15 which is provided with an opening in its upper end to receive the down turned flange 43 and the solenoid base. This flange 43, together with the upper portion of the solenoid and elongated bearing 44 turned upwardly from the bottom of the casing, provide for slidably receiving and properly centering a core 45 having an insulated lower portion 46 made of fibre or some other suitable material, a brass or other good conducting intermediate section 47 and a steel or other metallic upper section 48 adapted to be cut by the magnetic lines of force. The fibre or insulating section 46 is provided with a depressed portion or groove 49 to receive the rounded free ends of a pair of contact fingers 50 and 51 secured by binding bolts or screws 52 and 53 projecting through insulating blocks 54 and exposed on the exterior of the casing for coupling to the circuit wires.

45 A similar groove 55 is made in the intermediate brass section 47. A lever 56 is pivoted intermediate its ends in a bracket 57 depending from the bottom of the casing 15. This lever is provided with a rounded head 58 adapted to engage beneath the lower end of the solenoid core, while the opposite end of the lever receives a chain 59 or the like.

Referring to Fig. 6, the battery 60 is shown to be connected in circuit with the two controllers 10 and 11, the two controllers being in parallel. The leads 61 and 62 extend from one side of the battery 60 to like brushes on the two controllers. The opposite brushes of the respective controllers are connected by wires 63 and 64 to the upper ends of the solenoid windings 42. The return wires 65 and 66 connect in common with the opposite side of the battery 60.

65 The contact fingers 51 of the respective relays are connected by conductors 67 and

68 to the lamps 17 and 16 which are connected in multiple with one side of the battery 60 by the common return wire 69. The other contact fingers 50 are joined to the wires 65 and 66.

In operation, the brushes 28 and 29 are normally upon the insulated segments 26 and 27 in the position they are normally held by action of the spring 38 shown in Fig. 4. Suppose that the semaphore is set against the train and the trip 9 is elevated as shown in Fig. 1 then upon passage of the locomotive by this trip, the finger 13 of the right hand controller 11 will be struck and turned partially by impact. This connection will cause a partial rotation of the drum 23 sufficiently to turn the insulated segments 26 and 27 out of contact with the brushes 28 and 29, permitting the circuit to be closed through the brass drum. The circuit will be completed as follows; beginning at the battery 60 the current will flow through the lead 61 to the brush 28 through the drum 11 to the opposite brush 29 and thence by way of the wire 63 to and through the solenoid 42 completing the return to the battery through the wire 65. Becoming energized the solenoid 42 will eject its core downwardly to cause disengagement of the contact fingers 50 and 51 with the groove 49 and their engagement with the upper groove 55 of the brass intermediate section 47. The circuit is then established through the fingers 50 and 51 to the lamp 17. This lamp may be colored for instance red or green. In the case mentioned the lamp will preferably be red as the signal is set against the train.

On the other hand suppose the signal is set to show a clear track, then in this case the trip 9 will be down and the opposite trip 8 elevated in the path of the finger 12 of the opposite controller 10. Upon the passage of the train a circuit will be closed through the controller 10 and the companion solenoid which will result in the closing of the relay fingers and the illumination of the green lamp 16.

In Fig. 7 we have illustrated a slightly different form of circuit known as the closed circuit system.

Here the battery 60 is connected by the wires 61 and 62 with the brushes 28 of the controllers, but in this case the insulated segments of the controllers normally occupy a position at substantially right angles to that shown in Fig. 6 to permit of the brushes 28 and 29 bearing at all times against the brass drum whereby current may freely flow from one brush to the other. The wires 63 and 64 connect the brushes 29 with the coils of the relay A and B.

The relay coils are connected to the opposite side of the battery as shown. The relay switches are normally kept open by the closed circuit through the brushes 28 and 29.

and drum but as soon as the current is interrupted by the turning of the drum, the relay switch is closed in a well known manner. This causes current to flow from the 5 battery through the relay switch and winding 42 and return by either the wire 65 or 66 as the case may be. The core is then ejected and the appropriate light illuminated as above described.

10 In both cases the trip fingers of the controllers will be restored to initial position as soon as the trip arm has been passed because of the activity of the coil springs 38, and of course the other parts will be 15 turned to initial position at the same time thus opening or closing the circuit again according to its normal condition. However this rapid restoration of the primary circuits will not affect the secondary or light 20 circuit inasmuch as the spring ends of the contact fingers 50 and 51 will embrace the grooved brass intermediate part of the core and this position of the parts will persist until some active force makes the change 25 to the original position. This restoration is accomplished by the engineer drawing upon the chain 59 which causes the lever 56 to rock and its rounded head 58 to engage beneath and lift the core to the position shown 30 in Fig. 5.

It will be appreciated from the foregoing that the invention provides for bringing the signals closely to the attention of the engineer and to enable him to ascertain with precision the condition of the road or block 35 ahead and thereby surround the operation of trains with greater safety.

We have illustrated and described a preferred and satisfactory embodiment of our 40 invention, but it is obvious that changes may be made therein within the spirit and scope thereof as defined in the appended claims.

What is claimed is:

1. A signal mechanism including controllers on a locomotive having actuating fingers, a rock-shaft on the track having trip arms displaced angularly whereby to be elevated in the path of said fingers only successively, means for connecting said rock-shaft for 45 movement to a semaphore signal, primary circuits including said controllers, relays having coils also included in the primary circuits, said relays further including cores movable within the coils and having both 50 conducting and non-conducting portions, contacts bearing against said cores and adapted to be opened and closed by the conducting 55 and non-conducting portions, secondary

circuits including said contacts, signal means in the secondary circuits, and means to restore the cores to initial position, substantially as described. 60

2. A signal mechanism including controllers on a locomotive having actuating fingers, means actuated by a semaphore signal for 65 striking said actuating fingers, primary circuits including said controllers, relays having coils included in said primary circuits, said relays also containing solenoid cores having both conducting and non-conducting sections with grooves therein, spring contact bearing against said cores and adapted to take into the grooves thereof, secondary 70 circuits including said spring contacts, differently colored lamps in the secondary 75 circuits, and means adapted to be moved by hand to restore the cores to initial position, substantially as described.

3. A signal mechanism including controllers on a locomotive having actuating parts, 80 means on the track having trip members adapted to project into the path of said controller actuating parts, said trip members being connected to a semaphore signal, primary circuits including said controllers, relays also in the primary circuit and including solenoid cores having both conducting 85 and non-conducting sections, coils in the primary circuits arranged to influence said cores, contacts bearing against said cores, 90 secondary circuits including said contacts, a plurality of different signal means in said secondary circuits, and means adapted to be moved by the engineer to restore the cores to initial position, substantially as described. 95

4. A signal mechanism including controllers on a locomotive having actuating fingers, a rock-shaft on the track having trip arms set at substantially right angles to each other and connected for movement to a semaphore signal, said trip arms being in position to strike one or the other trip finger, primary circuits including said controllers, relays also in the primary circuits and including solenoid cores having both conducting 100 and non-conducting sections with grooves therein, coils to influence the cores, spring contacts, differently colored lamps in the secondary circuits, and levers moved by the engineer to restore the cores to initial 105 position, substantially as described. 110
